United States Patent Office.

ALEXANDER W. HALL, OF NEW YORK, N. Y.

Letters Patent No. 80,727, dated August 4, 1868.

IMPROVEMENT IN WASH-BOILERS.

The Schedule referred to in these Letters Patent and making part of the same.

TO ALL WHOM IT MAY CONCERN:

Be it known that I, ALEXANDER W. HALL, of the city, county, and State of New York, have invented a new and useful Improvement in Wash-Boilers; and I do hereby declare that the following is a full, clear, and exact description of the same, reference being had to the accompanying drawings, forming a part of this specification, in which—

Figure 1 represents an inner view of a wash-boiler constructed according to my improvement, as seen from above.

Figure 2 is a vertical section of the same, and

Figure 3 a sectional elevation of the same, represented at right angles with fig. 2.

Similar letters of reference indicate corresponding parts in the several figures.

This invention relates to wash-boilers, for cleansing clothing and other fabrics, and it consists in providing a circulating-chamber, arranged within the space between the bottom of the said shell and the bottom of the boiler, and having suitable communications with the shell and boiler, whereby the circulation of the water is rendered more certain, rapid, and uniform. This inner shell and circulating-device may be so constructed and combined that they require no special construction of the boiler, but are applicable to old boilers and those already in use, and, by being removable, afford facility for themselves being cleaned and cleaning the boiler.

To enable others to make and use my invention, I will describe it with reference to the drawings.

A is the boiler, made of the same form as an ordinary wash-boiler, or any other suitable form.

B is the inner shell or receptacle, of a form corresponding with the boiler, but sufficiently smaller to have a narrow space between their sides, and a deeper space between their bottoms, and a corresponding space above. This inner shell or receptacle B is kept in place within the boiler A by means of vertical stays or guide-rods a, which are secured to the outer wall of the shell B, and which extend far enough below to act as legs for the support of the said shell or receptacle B.

C is a chamber, rigidly secured to the bottom of the shell B, on the under side thereof, and communicating therewith by means of perforations or openings, e, between them, and which communicates with the interior of the boiler A through perforations or openings, b, in the sides of the said chamber C.

In the operation of this invention, the clothing or other textile fabrics are placed within the inner shell or receptacle B, and the boiler and shell are filled with water to about a level with the upper edge of the shell B, and the heat is applied, in the usual manner, at the bottom or bottom and sides of the boiler, and so soon as the water begins to boil, it rises and passing up through the space between the sides of the boiler and shell, overflows the latter. Simultaneously with this rise and overflow of the boiling water, the cooler water within the chamber C is supplying its place, through the openings b, and, in turn, the chamber C is being filled from the shell or receptacle B, through the openings e, and thus a continuous and rapid current through the shell B and the fabrics therein contained is established.

What I claim as my invention, and desire to have secured by Letters Patent, is—

The combination of the circulating-chamber C, attached to the shell B, with the boiler A, provided with apertures communicating with each, all constructed and arranged substantially as described.

A. W. HALL.
